UNITED STATES PATENT OFFICE.

CHARLES G. GROVER, OF NESCOPECK, PENNSYLVANIA.

REAMER.

1,163,083.

Specification of Letters Patent.

Patented Dec. 7, 1915.

Application filed September 8, 1914. Serial No. 860,744.

To all whom it may concern:

Be it known that I, CHARLES G. GROVER, a citizen of the United States, residing at Nescopeck, in the county of Luzerne and State of Pennsylvania, have invented a new and useful Reamer, of which the following is a specification.

The device forming the subject matter of this application is a reamer, and one object 10 of the present invention is to provide a reamer having a side cutter of novel form, novel means being provided for bowing the cutter outwardly.

Another object of the invention is to provide 15 a reamer in which the body portion thereof may be reversed, so as to present new edges for coöperation with the operative edges of the side cutter.

It is within the scope of the invention to 20 improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

In the accompanying drawing:—Figure 1 shows the invention in side elevation; Fig. 35 2 is a side elevation, the view point in Fig. 2 being 90 degrees remote from the view point in Fig. 1; Fig. 3 is an elevation similar to Fig. 1, the filler, however, having been removed and the side cutter being 40 shown as lying flat against the body portion of the reamer; Fig. 4 is a cross section on the line 4—4 of Fig. 1; Fig. 5 is a longitudinal sectional detail showing the means whereby the ends of the side cutter are assembled with the body of the reamer.

In carrying out the present invention there is provided a body 1 equipped at one end with a tang 2 and comprising a cylindrical portion 3, the body of the reamer being 50 of rectangular cross section adjacent one end, as shown at 4. The side faces of the squared end portion 4 converge toward each other, so that the portion 4 of the body of the reamer is of tapered form. Referring

to Fig. 4 it will be observed that this squared 55 portion 4 of the body of the reamer is provided with cutting edges 6, 7, 8 and 9.

Extended longitudinally of the body 1 is a cutter 10 which in cross section is of plano-convex form and is provided with 60 cutting edges 11 and 12. Adjacent its ends the cutter 10 is equipped with longitudinal slots 14. Securing elements 15 pass through the slots 14 and enter suitable openings formed in the body portion of the reamer. 65 Screws 16 are threaded into openings 17 formed in the body 1 of the reamer and constitute means whereby the cutter 10 may be bowed outwardly to any desired extent. The cutter 10 is resilient and when not engaged by the screws 16, lies against one side face of the body of the reamer, as clearly 70 shown in Fig. 3.

If desired, a filler may be interposed between the outer ends of the screws 16 and 75 the inner face of the cutter 10. The filler tapers toward its ends and may include a body 18 and a wear strip 20, the latter being adapted to receive the ends of the screws 16. 80

All parts of the structure, preferably are fashioned from metal, saving for the fact that, if desired, the body portion 18 of the filler may be made of wood.

As will be understood readily, the cutter 85 10 may be bowed outwardly by manipulating the screws 16, thereby to regulate the taper of the hole and to adjust the amount of reaming. The filler 18—20 may be omitted if desired as Fig. 3 will clearly indicate. 90

When the reamer is rotated in the direction of the arrow A in Fig. 4, the edge 11 of the cutter 10 and the edge 9 of the body portion of the reamer are operative. If, however, the reamer is rotated in the direction 95 of the arrow B, the edges 12 and 8 are effective. Should the edges 8 and 9, or either of them become dull, the body portion of the reamer may be rotated with respect to the cutter 10, under which circumstances, the 100 dulled edges 8 and 9 will be replaced, respectively, by the edges 6 and 7.

The slots 14 permit the resilient cutter 10 to be bowed to the desired extent, under the action of the screws 16.

The device herein disclosed is adapted to be employed for reaming bushings, bearings, and under any and all conditions of a like

sort, which call for a close and accurate fit between an inner and an outer or circumscribing part.

Having thus described the invention, what is claimed is:—

1. A reamer including a body; a transversely flexible side cutter extended longitudinally of the body; connections uniting the ends of the cutter with the body; means located between the connections for flexing the cutter transversely; and a removable filler inserted between said means and the cutter, the filler being independent of the connections and being held against the cutter by the flexing means.
- 15 2. A reamer including a body; a side cutter extended longitudinally of the body; connections uniting the ends of the cutter with the body, one of said connections being 20 slidable in the cutter; and body carried adjustable means engaging the cutter between the connections to effect an outward bowing of the cutter.
- 25 3. A reamer including a body; a side cutter extended longitudinally of the body, the side cutter being transversely flexible; means for connecting the cutter with the body; means on the body for producing an outward flexure of the cutter; the body 30 having cutting edges one of which coöperates with the cutter, the body being rever-

sible to cause the other of the cutting edges to coöperate with the cutter.

4. A reamer including a body; a side cutter extended longitudinally of the body; 35 connections uniting the ends of the cutter with the body, one of said connections being a slidable connection; body carried adjustable means engaging the intermediate portion of the cutter to effect an outward 40 bowing of the cutter, the body having cutting edges, one of which coöperates with the cutter, the body being reversible to cause the other of the cutting edges to coöperate with the cutter.

45 5. A reamer comprising a body; a transversely flexible side cutter extended longitudinally of the body and provided adjacent its ends with openings, one of which is elongated longitudinally of the body; securing 50 elements in the openings and engaging the body; and a screw disposed transversely of the body and threaded thereinto, the screw engaging the cutter intermediate the ends of the cutter.

55 In testimony that I claim the foregoing as my own, I have hereto affixed my signature in the presence of two witnesses.

CHARLES G. GROVER.
